UNITED STATES PATENT OFFICE.

HARRY H. BUCKLEY, OF CHICAGO, ILLINOIS, ASSIGNOR TO H. C. FRY GLASS COMPANY, OF ROCHESTER, PENNSYLVANIA, A CORPORATION OF PENNSYLVANIA.

DESIGN FOR A CUT-GLASS DISH OR SIMILAR ARTICLE.

44,914.

Specification for Design.

Patented Nov. 25, 1913.

Application filed September 25, 1913. Serial No. 791,868. Term of patent 7 years.

To all whom it may concern:

Be it known that I, HARRY H. BUCKLEY, a citizen of the United States, and residing at Chicago, in the county of Cook and State of Illinois, have invented a certain new, original, and ornamental Design for a Cut-Glass Dish or Similar Article, of which the following is a specification, reference being had to the accompanying drawings, in which—is a longitudinal section taken on line II—II of Fig. 1.

No novelty is claimed herein for the shape of the dish.

I claim:

The ornamental design for a cut glass dish or similar article, as shown.

HARRY H. BUCKLEY.
